REED FOR CIRCULAR LOOMS

Hermann Slowak, Montevideo, Uruguay

Application January 24, 1949, Serial No. 72,348
In Switzerland February 18, 1948

4 Claims. (Cl. 139—13)

1

The present invention relates to new and improved reed constructions for weaving on circular looms.

A primary object of the invention is the embodiment of novel and improved reed constructions of the aforesaid type, wherein an efficient structure is realized with a minimum of parts.

Briefly stated, the characteristic features of the reeds of the present invention which, as indicated, are especially adapted for use on a circular loom, are their annular shape and the fact that the reed strips or dents are secured at one end only, while the other end projects freely. A reed of this kind may thus consist essentially of an annular metallic body provided with notches or slots in which the dents, which may for example be stamped from sheet metal, are inserted. The particular shape of the dents may vary in accordance with the purpose for which the reed is to be used and in accordance with the manner in which the dents are secured on their support, since as will hereinafter appear this may be accomplished in various ways.

Presently-preferred embodiments of the invention, wherein the aforesaid object—as well as other objects and advantages—are realized, are hereinafter described in detail, with particular reference to the accompanying sheets of drawing, wherein:

Fig. 1 is a top plan view of a portion of an annular reed body according to a first form of the invention;

Fig. 2 is a cross-sectional view through the reed body, taken along line II—II of Fig. 1;

Fig. 3 is a perspective view of a reed dent corresponding to this type of reed body;

Fig. 4 is a sectional view corresponding to Fig. 2 but showing the parts in assembled relationship;

Fig. 5 is a top plan view of a portion of an annular reed body according to a second embodiment of the invention;

Fig. 6 is a cross-sectional view through the reed body, taken along line VI—VI of Fig. 5;

Fig. 7 is a perspective view of a reed dent corresponding to this second embodiment of the invention;

Fig. 8 is a sectional view taken along line VIII—VIII of Fig. 5 and showing the parts in assembled relationship;

Fig. 9 is a top plan view of a portion of an annular reed body according to a third modification of the invention;

Fig. 10 is a cross-sectional view through the reed body, taken along line X—X of Fig. 9;

2

Fig. 11 is a perspective view of a reed dent corresponding to the third form of the invention; and

Fig. 12 is a sectional view taken along line XII—XII of Fig. 9 and showing the parts in assembled relationship.

Referring first to the form of the invention illustrated in Figs. 1 to 4, the reed body is shown at 10. It will be understood that this body is associated with the loom in the conventional way and that, while only a portion is shown for the sake of economy of space, the entire reed body defines a complete annulus, the construction of the non-illustrated portion being the same as that of the illustrated portion. (This applies also to the reed bodies of the second and third embodiments of the invention, hereinafter mentioned.)

As shown more particularly in Figs. 1 and 2, 20 reed body 10 is provided with plurality of substantially equally spaced milled slots 11 which extend radially or almost radially and in each of which a reed dent 12 is adapted to be inserted and suitably secured. The depth of the slots is shown by the dotted line 13 in Fig. 2. The preferred shape of dent 12 for this embodiment of the invention is shown in Fig. 3.

Annular recesses 14 and 15 are provided on the inner and outer lateral surfaces of reed body 10, as shown in Fig. 2. At its upper end, each slot 11 opens into recess 14, while at its lower end it opens into recess 15.

The dent 12 comprises an inclined median portion 16 which, when the parts are assembled, is positioned in its slot 11, the upper inclined edge 17 being essentially flush with the upper inclined surface of reed body 10. Each dent 12 also comprises a free upwardly-projecting end, which may be configured as shown in Fig. 3 or may be suitably bent or thickened or arched at certain points. Each dent 12 further comprises two spaced downwardly extending legs 18, 19 which, in the assembled device, are seated respectively on the floors of recesses 14 and 15; see Fig. 4.

45 Rectangular recesses 20 and 21 are provided respectively in the outer edges of legs 18 and 19, their location being such that, as shown in Fig. 4, they can overlap respectively with recesses 14 and 15 to provide grooves for the reception of wire securing members 22 and 23, shown in cross section in Fig. 4. The free ends (not shown) of these wire members may be clamped and soldered or otherwise fastened together, thereby insuring firm positioning of the dents.

55 Figs. 5, 6, 7 and 8 of the drawings disclose a

second relationship of parts according to the invention. The reed body 30, being as before adapted for use on a circular weaving loom, is annular. In this embodiment, however, the cross-sectional configuration of the body 30 is specifically different from that of the previously-described reed body 10; see, more particularly, Fig. 6. Moreover, the specific configuration of the corresponding dents 31 (Fig. 7) differs from that of dents 12 of the first embodiment of the invention.

The reed body 30 may be aptly described as of modified inverted-T configuration. The cross-piece of the T is rabbeted at one corner to provide a recess 32, the purpose of which is hereinafter described. The stem 33 of the inverted T projects upwardly and is beveled off, as at 34. The upstanding projection 33 is, of course, annular (see Fig. 5) and narrow grooves 35 of slight depth are cut on the inside and outside lateral surfaces thereof, the said grooves being radially alined in pairs and extending exactly or approximately in the direction of the axis of the reed as can be seen from Fig. 5.

The dents 31 may be aptly described as of modified inverted-Y configuration, the downwardly-extending arms of the inverted-Y being adapted, when the parts are in assembled relation, to straddle the rib 33 while being inserted in the corresponding grooves 35, the free ends of the arms extending respectively into recesses formed in the upper surface of the cross-piece of the reed body 30; see Fig. 8. For securing the dents 31, there are provided a plurality of flat stay bolts 36, each provided with an eye adjacent each end, as may be seen from Fig. 8.

The assembly of the parts may be conveniently effected by first arranging the dents 31, which for this purpose are provided with correspondingly located openings 37 (Fig. 7), in rows on an annular sheet metal strip 38 (shown in section in Fig. 8, and whose free ends may be tied together in any desired conventional manner such as soldering or the like)—a stay bolt 36 being inserted after each certain number of dents as determined by the position of the boreholes 39 in the reed body (see Fig. 5). The thus-assembled parts are then mounted on the annulus 33, the projecting parts of the stay bolts being passed through the corresponding boreholes and the dents being fitted into the corresponding grooves 35. Finally, shims or wedges 40 are severally inserted through the eye in lower end of each stay bolt, which end projects into cut-out recess 32, hereinbefore described. The stay bolts may be provided, if desired, with threaded cylindrical lower ends so that the fastening may be achieved with the aid of nuts screwed thereon.

Still another type of construction of the reed ring and dents is illustrated in Figs. 9, 10, 11 and 12. Here, the ring assumes the form of a hollow annulus 41 which is essentially U-shaped in cross sectional configuration (Fig. 10) and the grooves 42, in which the corresponding dents 43 are inserted, are cut on the two inside walls of the ring. The ring 41 with the radial grooves 42 extending in the exact or approximate direction of its axis is shown in plan view in Fig. 9. The corresponding dents 43 are shown in Fig. 11.

The dents are, in this embodiment of the invention, secured on the reed body with the aid of a flat metallic holding ring 44, the free ends of which may be tied together in any desired way, as by means of solder or the like. This ring 44 runs through the horizontal portions of the key slots 45, one of which is provided in the lower

end of each dent 43. A second ring 46, shown in section in Fig. 12, passes through the openings 47 correspondingly provided in the dents (Fig. 11).

In assembling these parts, the dents 43 are first arranged in rows on these two rings 44, 46 and are then inserted in the grooves 42. Then, screws 48 (Fig. 12) are inserted from below through corresponding boreholes 49 (Fig. 10) in the bottom of the reed body 41, and are screwed into threaded openings provided in the holding ring 44. Fig. 12 shows the assembled parts.

The scope of this invention extends to still other variants besides the three illustrative examples herein described.

It is possible, for example, for the free projecting end of the reed dent as shown in Fig. 7 to be given a shape as shown in Fig. 3, and it may also be provided with a hole through which a wire ring can be drawn, just as the dent shown in Fig. 20 11 comprises the hole 47 through which the wire ring 46 is drawn.

An example of another combination that can be made is one in which use is made of the stay bolts shown in Fig. 8 instead of the flat ring 44 for securing the reed dents shown in Figs. 11 and 12. In this case, the dent shown in Fig. 11 has no recess formed in it, but a hole is punched in the middle of the dent like the one indicated at 37 in Fig. 7, so that the securing can be effected by means of the ring 38 (Fig. 8) as described for the example of the second type.

In the reeds illustrated in the drawings, the dents are positioned vertically and radially on their support, but the dents may be so positioned that the angle formed by them with the reed ring is less than 90 degrees, or that they are not exactly radial but positioned in an approximately radial direction.

The reed dents employed in the above given examples are flat and level. It is however of advantage to slightly curve the ends of the dents that engage in the slots made in the reed body.

A particular type of construction of a reed consists in using dents whose free projecting ends are suitably bent, or else thickened or arched at certain points.

Having thus disclosed the invention, what is claimed is:

1. A reed for a circular loom, comprising an arcuate reed body having a dent-supporting portion, said portion being provided with a pair of spaced arcuate series of slots extending substantially in the direction of the axis of the reed, a slot of each series being in radial alinement with a corresponding slot of the other series, a dent mounted in each pair of corresponding slots, the juxtaposed edge portions only of said dents being received in said slots, and means for securing said dents to said reed body.
2. A reed for a circular loom, comprising an arcuate reed body having a dent-supporting portion, said portion having the configuration of an arcuate rib and being provided with a pair of spaced arcuate series of slots extending substantially in the direction of the axis of the reed, one of said series being disposed on one side of said rib and the other series on the other side, a slot of each series being in radial alinement with a corresponding slot of the other series, a dent mounted in each pair of corresponding slots, the juxtaposed edge portions only of said dents being received in said slots, and means for securing said dents to said reed body.
3. A reed for a circular loom, comprising an arcuate reed body having a dent-supporting por-

tion, said portion comprising a pair of spaced upright walls and being provided with a pair of spaced arcuate series of slots extending substantially in the direction of the axis of the reed, one of said series being disposed on the inner side of one of said walls and the other series on the inner side of the other of said walls, a slot of each series being in radial alinement with a corresponding slot of the other series, a dent mounted in each pair of corresponding slots, the juxtaposed edge portions only of said dents being received in said slots, and means for securing said dents to said reed body.

4. A relationship of parts according to claim 1, wherein the dents are bolted to said body. 15
